US0D1037842S

(12) **United States Design Patent** (10) Patent No.: **US D1,037,842 S**
(45) Date of Patent: ** Aug. 6, 2024

(54) **WIPES DISPENSING CANISTER WALL MOUNTING BRACKET**

(71) Applicant: **GOJO Industries, Inc.**, Akron, OH (US)

(72) Inventors: **Christopher J. Mann**, Hudson, OH (US); **Mark E. Rosenkranz**, Akron, OH (US); **Richard E. Corney**, Akron, OH (US); **Matthew Hern**, Malibu, CA (US)

(73) Assignee: **GOJO Industries, Inc.**, Akron, OH (US)

(**) Term: **15 Years**

(21) Appl. No.: **29/836,271**

(22) Filed: **Apr. 26, 2022**

Related U.S. Application Data

(63) Continuation of application No. 29/712,855, filed on Nov. 12, 2019, now Pat. No. Des. 953,151.

(57) **CLAIM**

The ornamental design for a wipes dispensing canister wall mounting bracket, as shown and described.

DESCRIPTION

FIG. 1 is a perspective view of a wipes dispensing canister wall mounting bracket of the new design;

FIG. 2 is a top plan view of the wipes dispensing canister wall mounting bracket of the new design;

FIG. 3 is a front elevational view of the wipes dispensing canister wall mounting bracket of FIG. 1;

FIG. 4 is a bottom view of the wipes dispensing canister wall mounting bracket of FIG. 1;

FIG. 5 is a rear elevational view of the wipes dispensing canister wall mounting bracket of FIG. 1;

FIG. 6 is a left side elevational view of the wipes dispensing canister wall mounting bracket of FIG. 1;

FIG. 7 is a right side elevational view of the wipes dispensing canister wall mounting bracket of FIG. 1; and,

FIG. 8 is a perspective view of the wipes dispensing canister wall mounting bracket of FIG. 1 with a wipes dispensing canister.

The broken lines shown in the Figures represent environment and portions of the wipes dispensing canister wall mounting bracket that form no part of the claimed design.

1 Claim, 5 Drawing Sheets
